[57] CLAIM

The ornamental design for a combined table and sectional sofa unit, as shown.

DESCRIPTION

FIG. 1 is a perspective view of a combined table and sectional sofa unit showing my new design;

FIG. 2 is a right side elevational view;

FIG. 3 is a left side elevational view;

FIG. 4 is a left rear elevational view;

FIG. 5 is a right rear elevational view; and,

FIG. 6 is a top plan view thereof.

FIG. 1 has been drawn to a larger scale with respect to the other views.

FIG. 1

FIG. 2

FIG. 3

FIG. 4

FIG. 5

FIG. 6
